(57) **CLAIM**

The ornamental design for a snap on outlet faceplate, as shown and described.

DESCRIPTION

FIG. 1 is a perspective view of one embodiment of a snap on outlet faceplate showing our new design;

FIG. 2 is another perspective view thereof;

FIG. 3 is a front view thereof;

FIG. 4 is a back view thereof;

FIG. 5 is a side view thereof, the opposite side being a mirror image thereof; and,

FIG. 6 is a top view thereof, the bottom view being a mirror image thereof.

In the drawings, the broken lines are for the purpose of illustrating portions of the article that form no part of the claimed design.
